IGNITION SYSTEM FOR OIL BURNERS
AND THE LIKE

Emil R. Capita, New York, N. Y.

Application May 6, 1932, Serial No. 609,601

3 Claims. (Cl. 158—28)

My invention relates to a new and improved ignition system for oil burners and the like, and a new and improved method of controlling the ignition system or circuit of oil burners or the like.

5 One of the objects of my invention is to provide an improved ignition system for oil burners of the type in which the fuel is intermittently fed and ignited, it being understood however, that my invention applies to every type of oil burner, 10 viz the gun type, rotary or the like.

Another object of my invention is to provide a method of controlling the ignition in an oil burner in which a blower motor is employed for atomizing and injecting oil into the fire box, in 15 which the transient reactance values of the different parts of the circuit causes a maximum current to be initially supplied to the ignition device, said reactance being automatically changed when the blower motor is in full operation, so 20 that the supply of current to the ignition device is maintained in order to produce continuous ignition of the oil. However, the invention is also applicable to oil burners in which the ignition circuit is interrupted after the flame has been 25 produced. In either case, the major portion of the reactance of the circuit is supplied by the blower motor after the ignition has been secured and the blower motor is in full operation.

Another object of my invention is to provide a 30 special system in which the oil will be ignited by means of a concentrated heater resistance element (in contradistinction to a spark or arc), the circuit being so adjusted and the resistance element being so selected as to prevent any 35 "shorting" of the heater resistance element.

Other objects of my invention are to provide improved safety devices whereby the circuit will be broken if the ignition device fails to operate or is thrown out of operation for any reason.

40 Other objects of my invention will be set forth in the following description and drawing which illustrates a preferred embodiment thereof, it being understood that the above general statement of the objects of my invention is intended 45 merely to generally explain the same and not to limit in any manner.

Fig. 1 is a diagrammatic view illustrating one embodiment of the invention.

Fig. 2 illustrates another embodiment, having 50 a different form of safety device.

Fig. 3 illustrates a third embodiment of my invention having a third form of safety device.

Fig. 4 shows a fourth embodiment of my invention in which the ignition is secured by means 55 of a heater resistance element instead of utilizing

ing the spark gap which is shown in Figs. 1-3 inclusive.

Fig. 5 is a diagrammatic view showing how a straight concentrated heater resistance element of special composition is employed instead of a 5 wire heater resistance element of the type shown in Fig. 4.

Fig. 6 illustrates a different type of safety device.

It has heretofore been well known that the 10 conventional jump spark oil burner electric ignition equipment consists of a set of electrodes forming an air gap directly in front of the nozzle or within the zone of the flame, supplied with high tension current from a high reactance transformer connected in parallel to the blower motor. With this method, the transformer is thrown across the supply line simultaneously with the 15 motor.

It has been found that even though surplus 20 voltage was supplied during normal operation, that on numerous occasions the spark failed to strike across the ignition electrodes, causing failure of ignition and other complications. I have discovered that the reasons for these failures are 25 as follows:—

Upon closing the line switch, the drop of line voltage due to the large starting current of the blower motor resulted in a proportional drop of the transformer secondary voltage, so that the 30 secondary voltage was insufficient to strike across the gap. However, after the blower motor came up to speed and the voltage to normal, the air blast and oil vapor passing between the ignition electrode points raised the breakdown potential 35 across the gap above the voltage which the transformer was able to supply.

As reference, it may be borne in mind that it requires a much higher voltage to jump across a 40 non-ionized gap than to maintain an arc across the same gap subject to identical conditions.

With my method, as shown in Fig. 1, I connect the primary of a low reactance ignition transformer in series with the motor. In this installation the motor and transformer primary must 45 be wound so as to operate at their rated volt-ampere input when the oil burner is in operation.

The cycle of operation with the series connected circuit is as follows:—

When the circuit is closed, the circuit of the 50 secondary coil is open. The impedance of the transformer is then greater than the impedance of the motor, because the rotor of the motor is then stationary or operating at very low speed. The motors which are generally used in these 55

devices are split-phase motors, which have a low starting torque. At this moment, the voltage drop across the transformer is greater than the voltage drop across the motor, so that a transient and 5 very high secondary voltage is induced at the ignition electrodes. As the motor speeds up its impedance is increased. After the spark strikes across the ignition electrodes, the path is highly ionized and an arc is formed. This in turn practically short-circuits the secondary coil of the 10 transformer reducing its impedance and the voltage drop across the primary windings. The reduction of transformer impedance results in a higher voltage drop across the motor, causing the 15 same to start rotating. The rest of the cycle is as usual.

With the series circuit as shown in Fig. 1, the 20 spark or arc is strongest during the moment of starting and the spark or arc is formed before the motor starts rotating and before the air blast and oil vapor are able to increase the break-down potential difference between the ignition electrodes.

The safety gap between auxiliary electrodes G1 25 and G2, connected across the secondary winding of the transformer, is adjusted to strike below maximum secondary voltage and above the required operating voltage for producing the spark or arc at the ignition electrodes. A fuse wire F 30 is connected in series with the supply line located just above the safety gap and within its arc path so that the fuse wire is melted by the auxiliary arc, thus opening the line current, should the striking potential at the ignition electrodes exceed a pre-determined value.

In Fig. 1, the current is supplied through line wires L' and L².

Fig. 2 shows the connection in series of the blower motor and transformer circuit. Connected across the secondary of the ignition transformer is a magnetic relay connected in series with a safety gap which breaks the blower motor circuit, should the potential across the ignition electrodes exceed the safe operation of the system.

The primary circuit during normal operation (Fig. 2) is as follows:—

Supply current enters from L1 and passes through lead 13, through spring contact 11, through contact 12, through flexible pigtails 10, 50 through lead 14, through primary IP of transformer I, through blower motor 2 and back to line L2.

The secondary circuit is as follows:—

Electrodes 3A and 3B are connected to the high 55 tension ends of the secondary 1S of transformer I. The relay circuit is as follows: Starting with one end of the secondary, going through relay winding 5 connected at 16 to relay core 4, through relay armature 15, through gap 6, through lead 7, 60 and back to other pole of the secondary windings of the ignition transformer. The cycle of operation is as follows:

Should the potential across 3A and 3B exceed the safety limit, high tension current will flow 65 through coil 5 to connection 16, through core 4, through armature 15, through safety gap 6, returning through lead 7 to the transformer secondary. A magnetic field in core 4 will attract armature 15 which is pivoted at point 8, causing a lifting action of insulator bar 9, which, having a hook-shaped contact 12 attached to it will release 70 spring blade 11, and thus break the primary line circuit between circuit-breaker blade 11 and contact 12, causing blade 11 to assume position indicated by reference numeral 36. The breaking of

the circuit by this relay will indicate the necessity of cleaning and adjusting the ignition electrodes. This relay is manually reset.

Fig. 3 also shows the series connection of the 5 transformer and blower motor in the oil-burner ignition circuit, in which I use a thermo blade relay in series with a safety gap connected across the transformer secondary output for the purpose of breaking the line current in case of excessive potential difference across the igniter electrodes.

The primary circuit: Line current from L1 passes through 22, through blade 21, through junction 26, through thermo blade 20, through mounting stud 24, through lead 23, through primary IP of transformer I, through blower motor 2, and back into L2. This is the operation of the system under normal conditions. However, should the potential across 3A and 3B exceed the 20 limits of safe operation, a gap between 17 and 18 will strike causing an arc to form which in turn will heat the thermo blade 20. This thermo blade, which has a hook 26 at its free end, is adjusted so that the heat applied to it will cause same to 25 warp away from blade 21, opening the primary circuit at this point, by permitting spring blade 21 to assume the position indicated by reference numeral 37. A mica insulator 19 or any suitable 30 insulator is placed above auxiliary gap 25 and below thermo blade 20 for providing electrical insulation between the primary and secondary circuits.

Fig. 4 shows an ignition system for oil burners in which a heater resistance wire is located within the zone of the flame. This heater resistance 35 is connected in series with the blower motor. The function of this system is as follows: When line current from L1 and L2 is supplied, the blower motor rotor now being initially stationary, will represent a very small proportion of the impedance in this circuit. Hence the largest portion of the voltage drop, and the large wattage 40 consumption will take place across terminals 34 and 35 of the igniter resistor, which during the starting of the motor, will be heated to a temperature high enough to ignite the vaporized oil. Directly after the rotor of the motor comes up to 45 normal speed, the increase of impedance in the motor will result in a reduction of current flow which in turn will reduce the heating effect of igniter resistor 29, thus automatically producing a high temperature in the igniter resistor before the atomized oil is blown into the fire box, and automatically reducing the current flow through the resistor during operation. Should the resistor 50 in this circuit burn open, the opening of same will break the motor circuit, making the system inoperative and therefore avoiding the possibility of pumping into the furnace a quantity of vaporized fuel, thus eliminating fire hazards. The fuel-supply pipe 27 has the usual outlet 28.

Fig. 5 shows an ignition system for oil burners in which a straight heater resistance element 40 is held between clips 38 and 39, and is connected 65 in series with the blower motor. The function of the system is as follows:

When line current is supplied through L1 and L2, the blower motor rotor, being initially stationary, will represent a very small proportion of the impedance in this circuit, causing the largest 70 proportion of voltage drop and therefore large wattage consumption to take place across terminals 38 and 39 of the igniter resistor. During the starting of the motor this resistor will be 75 heated to a temperature high enough to ignite

the vaporized oil. Directly after the motor comes up to normal speed, the increase of impedance in the motor will result in a reduction of current flow which in turn will reduce the heating effect of igniter resistor 40, thus automatically producing a high temperature in the igniter resistor before the atomized oil is blown into the fire box, and automatically reducing the current flow through the resistor during operation. Should the resistor in this circuit burn open, the opening of the same will break the motor circuit, making the system inoperative and therefore avoiding the possibility of pumping into the furnace a quantity of vaporized fuel with the resultant fire hazard.

The resistor 40 may be made of any suitable silicon carbide (carborundum) or carbon graphite composition having a high resistance within a relatively small mass so that the momentary high wattage consumed therein will cause the same to attain a temperature above the ignition requirements of the atomized oil and air mixture. Preferably, the resistor 40 is made in a straight piece in order to avoid excessive heating which results when a helically wound wire resistor is used, in which case carbon deposits between adjacent turns tend to short circuit these turns. I also take advantage of the negative resistance characteristics of the resistor 40 as from my observation, when some of these materials were brought to a high temperature their resistance was reduced causing less wattage to be consumed with same.

Fig. 6 shows the series connection of the blower motor and transformer circuit. Connected across the secondary of the ignition transformer is a relay actuated through the burning apart of a string or the like, should the potential across the ignition electrodes exceed the safe operation potential of the system.

The primary circuit during normal operation (Fig. 6): Current enters at L₁, passes through wire 41, through blade 42, through contact 43, through wire 44, through primary coil 1P, through blower motor 2, returning to L₂.

The secondary circuit during normal operation (Fig. 6): Electrodes 3A and 3B are connected to the high tension ends of the secondary coil 1S. The relay circuit is as follows: Starting with one terminal of the transformer secondary coil 1S, hence to safety gap electrode 45, through gap 46 to electrode 47 and returning to other terminal of transformer secondary 1S. A piece of string (this string member may be made of any combustible material) is fastened to the support 50. This string member passes through the arc zone of the safety gap 46 and it holds the blade 42 in the full line position shown in Fig. 6.

Should the potential across 3A and 3B exceed the safety limits, an arc will strike between safety gap electrodes 45 and 47 causing member 49 to burn apart, thus permitting the blade 42 to spring to the dotted line position 42A and opening the supply line circuit.

While I do not wish to be limited to the constants stated herein, I can give the following as the result of some practical experiments.

Utilizing a popular make of oil burner, the current momentarily consumed when the line circuit was closed was approximately 18 amps. At full motor speed, the current diminished to 3.5 amps. Hence, when the system began to operate, there was a consumption of 1800 watts in the resistor described in Figs. 4 and 5, and this

diminished to 60 watts. Referring to Fig. 4, the resistor 28 has a total resistance of about 5 ohms when it is cold and it had acquired a temperature of about 2400° F. with the momentary starting current of 18 amps.

Referring to the embodiments utilizing a spark gap, under normal operating conditions and at normal speed, the motor had a total impedance of substantially 28 ohms. This consisted of a reactance of 26.9 ohms and a resistance of 7.6 10 ohms. The insertion of the ignition transformer in series increased the resistance component to 12.44 ohms, thus increasing the impedance to 29.6 ohms. When the motor is operating at normal speed, its impedance largely consists of its 15 reactance, and the addition of 4.84 ohms to the resistance component of the reactance, did not produce any noticeable difference in the normal operating speed of the motor.

In the ignition system now used, the starting 20 current is in excess of 25 amps. According to my improved method, the starting current is brought down to approximately 18 amps.

For the purposes of this specification, the resistors 29 and 40, and the separated ignition 25 electrodes may be referred to as an ignition device. In each of the embodiments specified herein, it may be stated that the ignition device is coupled in series to the blower motor, because the transformer is in effect an inductive coupling. 30

When the circuit of the ignition system is closed, it will be noted that the full line voltage is simultaneously impressed upon the motor and upon the ignition device. Likewise, the voltage drop across the ignition device has a transient 35 value and this transient value varies in such manner as to reduce the voltage drop across the low tension supply of said ignition device, when the motor has reached its normal predetermined speed.

In the shunt circuit system which is now in use, it is customary to use a transformer having a high reactance, as for example, a reactance of 100%. In the series circuit which I have devised, I prefer to use a transformer having a reactance 45 which is as low as commercial construction will permit. As is well-known, a low reactance transformer has very close coupling between its primary and secondary coils, so that the stray flux is minimized. Hence, the power factor of the 50 transformer which I utilize is much higher than the power factor of the type of transformer which is now used in the shunt circuit. For example, I utilize a transformer having a power factor which is substantially unity, whereas the power 55 factor of the transformer used in shunt is seldom as high as 70% and ordinarily rates between 40% and 50%.

Another characteristic of my circuit is that the impedance of the blower motor acts as the reactive or current-limiting component of the circuit of the ignition transformer. That is, the impedance of the blower motor acts in effect as a choke coil to limit the current supplied to the spark or arc which is formed across the terminals of 65 the secondary coil. It has been assumed for the purposes of this specification that ordinary commercial alternating current is utilized.

According to my invention, I can temporarily overload the transformer at the moment when the 70 line switch is closed and before the blower motor begins to turn, and during the period while the blower motor is attaining its normal predetermined speed. From this viewpoint as well as from other viewpoints, the use of a low reactance 75

transformer is an important feature, because it permits the motor to attain and to keep its normal predetermined speed while the oil is being injected and ignited.

5 I claim:

1. A control system for an oil burner having a blower motor and a spark ignition means, comprising a motor circuit having a main control switch and the primary coil of a transformer connected in series with the blower motor, ignition electrodes connected to the terminals of the secondary coil of said transformer, auxiliary electrodes connected in parallel with said ignition electrodes and forming an auxiliary gap materially greater than the gap between said ignition electrodes, and control means operable in response to the passage of current across said auxiliary gap to open said main switch.
2. A control system for an oil burner having a blower motor and a spark ignition means, comprising a motor circuit having a main control switch and the primary coil of a transformer connected in series with the blower motor, ignition electrodes connected to the terminals of the secondary coil of said transformer, auxiliary electrodes connected in parallel with said ignition electrodes and forming an auxiliary gap materially greater than the gap between said ignition electrodes, and control means operable in response to the passage of current across said auxiliary gap to open said main switch.

ally greater than the gap between said ignition electrodes, and control means operable in response to the passage of current across said auxiliary gap to open said main switch, said transformer having a reactance which is sufficiently low in relation to the reactance of the motor so as to cause said transformer to be overloaded during the period in which said motor is attaining its normal predetermined speed. 5

3. A control system for an oil burner having a blower motor and a spark ignition means, comprising a motor circuit having a main control switch and the primary coil of a transformer connected in series with the blower motor, ignition electrodes connected to the terminals of the secondary coil of said transformer, auxiliary electrodes connected in parallel with said ignition electrodes and forming an auxiliary gap materially greater than the gap between said ignition electrodes, and control means operable in response to the passage of current across said auxiliary gap to open said main switch, the impedance of the motor exceeding fifty per cent of the total impedance of the circuit when the motor is operating at normal speed and the spark ignition means are operative. 10 15 20 25

EMIL R. CAPITA.
